UNITED STATES PATENT OFFICE.

WILLIAM ASBURY, OF NEW YORK, N. Y., ASSIGNEE TO THE AMERICAN SAFETY APPLI-
ANCE COMPANY, A CORPORATION OF MAINE.

CONTAINER.

1,053,344.

Specification of Letters Patent. Patented Feb. 18, 1913.

Application filed January 25, 1908. Serial No. 412,680.

To all whom it may concern:

Be it known that I, WILLIAM ASBURY, a subject of the King of Great Britain and Ireland, residing in the city, county, and State of New York, have invented a new and useful Improvement in Containers, of which the following is a specification.

This invention relates to improvements in containers and more particularly in containers for gasoline, kerosene, benzine, ether or other volatile or inflammable liquids, and has for its object a container into which or from which such liquids can be poured or withdrawn and in which such liquids can be kept or conveyed without danger of explosion.

The invention is illustrated in the accompanying drawings which form part of this specification.

Figure 1 is an elevation of a vertical section of a container made in accordance with this invention. Fig. 2 is a plan view from below of parts surrounding the lower end of the tube shown in Fig. 1, the gauze shown in Fig. 1 being partly removed in Fig. 2. Fig. 3 is a plan view from above of the valve covering the upper end of the tube shown in Fig. 1. Fig. 4 is an elevation of a vertical section of a modified form of a container made in accordance with this invention. Fig. 5 is a plan view from below of parts surrounding the lower end of the tube shown in Fig. 4. Fig. 6 is a plan view of the split ring H shown in Fig. 4. Fig. 7 is an elevation of a vertical section or part of a container made in accordance with this invention. Fig. 8 is an elevation, partly in vertical section, of a container made in accordance with this invention. Fig. 9 is an elevation of the right side of the part attached to the bottom of the containers shown in Figs. 1 and 4. Fig. 10 is an elevation of a vertical section made as indicated by the line α shown in Fig. 1 of the part shown in Fig. 9, the arrow in Fig. 1 showing the direction of the view. Fig. 11 is a plan view of the key shown in Figs. 1 and 4. Fig. 12 is an elevation of a vertical section showing the key hole into which the key shown in Fig. 12 fits, as shown in Figs. 1 and 4.

Referring to the several figures of the drawings, A is the body of the container which may be of any suitable and conven-

ient size and form and which may be made of any suitable material, such as sheet metal. In Fig. 1 the container is made of thicker material than is the container shown in Fig. 4. The body of the container is provided with two openings, one being, preferably, in the top and the other being, preferably, in the bottom for the reception of the conduit or tube B and its connected parts.

Referring to Figs. 1 and 2, C C are collars, each of which may be provided with screw-threads t on the outside and inside and with two flanges c and c' . The flanges c are, as shown, perforated by the parts or openings D and provided internally with screw-threads. The openings of the container may be provided with screw-threads and the collars C screw into, or are otherwise fitted to, the openings, as shown in Fig. 1. E E are rings of gauze extending across the openings D. F F are thimbles, each of which may be provided with screw-threads on the outside and with a flange f at one end. The thimbles F screw into, or are otherwise fitted to, the flanges c of the collars C, and the external parts of flanges f of the thimbles F overlap and support the rings E of gauze.

In constructing a container, according to this invention, the parts C, E and F are first adjusted in one opening of the container and one end of conduit B is then adjusted in thimble F, as shown in Fig. 1. Then parts C, E and F are adjusted in the other opening of the container and to the other end of conduit B, as shown in Fig. 1.

In Figs. 7 and 8, the construction and adjustment of parts A, B, C, D, E and F are similar to the construction and arrangement thereof shown in Fig. 1. As shown in Figs. 1, 7 and 8, space intervenes between the ends of conduit B and internal parts of flanges f of thimbles F, allowance being thus made for the longitudinal expansion and contraction of conduit B.

Referring to Figs. 4, 5 and 6, G G are collars provided with projecting parts g which may have screw-threads t on the outside and inside. The collars G are adjusted to the exterior of the body of the container about the openings of the container. The collars G are, preferably, provided with recesses, as at g' , and the body of the container in such case is bent to correspond to and to

fit into the recesses. H H are rings adjusted to the interior of the body of the container and provided with screw-holes corresponding to perforations in the body of the container and in the collars G through which screws I pass into the screw-holes of the rings H, binding the parts mentioned firmly together and making a gasket of the parts of the body of the container between the collars G and the rings H. The joint thus made is a solid, tight joint. The rings H, illustrated in Fig. 6 and, by dotted lines, in Fig. 5, are split as at J to permit the rings to be contracted until they become small enough to be inserted through the openings of the container in order that they may be adjusted, as above described, to the interior surface of the body of the container. As shown in Fig. 4, the conduit B may be provided at one end, the upper end in Fig. 4, with a flange K resting upon the collar G, while space is left at the other end of the conduit B to permit the longitudinal expansion and contraction thereof.

25 Referring to Figs. 1, 4, 9, 10, and 12, L is a hollow, metal-cast or piece of suitable material provided with a central core M having a bore N extending through it. In the bore N is a rotatable stopper or cylinder O provided with an inlet P for air and an outlet Q for liquids, the inlet and outlet being separated as shown in Figs. 1 and 4. The rotatable cylinder O is provided with a perforation R which communicates with the air-inlet P and with a perforation S which communicates with the liquid-outlet Q, and the core M is provided with perforations T and U corresponding, respectively, to the perforations R and S, but of smaller width. The cylinder O tapers at one end and the bore N of the core M correspondingly tapers to receive the tapering end of the cylinder O, as shown in Figs. 1 and 4. V is a cap secured to the core M, as by screw-threads, and covering the bore N. The cap V is provided with a perforation W corresponding to the air inlet P, and is so shaped, as clearly shown in Fig. 12, as to receive the key X shown in Fig. 11 and to permit the key to turn within it, thus forming part of a key-hole as well as a channel for air through the cap V to the air-inlet P. As shown in Fig. 12, the end of the rotatable cylinder O is provided with recesses Y Y which complete the key-hole and receive the sides of the end or end of the key X when the key is inserted in the key-hole. A spring Z surrounds one end of the cylinder O, between the cap V and the opposite ledge with which the cylinder O is provided, and by reason of the pressure exerted by the spring, the tapered end of the cylinder O is constantly pressed into the tapered part of the bore N and because of such constant pressure and the greater width of the per-

forations R and S, the proper adjustment of the cylinder O and of its perforations R and S to the corresponding perforations T and U is not lost through wear of the tapered end of the cylinder or other parts. When the key X is inserted in the key-hole and turned, the rotatable cylinder O will revolve in one direction or in the other, as desired, and the perforations R and S may be brought opposite to and in communication with, or away from and out of communication with, the corresponding perforations T and U. The perforation U opens into the hollow cavity l of the fitting or casting L surrounding its core M. The perforation T opens into a pipe 1 suitably connected therewith. The cavity l communicates with the body of the container either through openings D, as shown in Fig. 1, or through perforations d in conduit B, as shown in Fig. 4. The key-hole is, as shown, preferably, so constructed that the key cannot be withdrawn until communication between the air-inlet P and liquid-outlet Q and the body of the container has been shut off; hence, the key will always be visible when the communication exists.

As shown in the drawings, Figs. 1, 7 and 8 and Fig. 4, the collars G and the collars G may be provided with internal screw-threads, as shown, or with external screw-threads, or with both internal and external screw-threads, as is the case with the collars G, as shown, for the attachment and adjustment to the containers at the openings thereof of the several caps or fittings, shown in the drawings, which are provided with external or internal screw-threads as required for the purpose of such attachment and adjustment; or the several fittings may otherwise be suitably attached and adjusted to the containers at the openings thereof. In Figs. 1, 4 and 8, the fitting 2 is a valve and valve-seat attached and adjusted as described to the container at the upper opening thereof and covering and protecting the same. The pressure of the spring 3 upon the valve 4 is such as normally to maintain the valve in position upon its seat 5, and to permit the valve 4 to rise and gas or air to escape from within the container before pressure of gas within the container becomes strong enough to burst the container. In Figs. 1 and 4 the fitting L provided with the air-inlet P and liquid-outlet Q above described is shown adjusted and attached to the container at the lower opening thereof. In Fig. 7, 6 is a blow-out plug or device attached to one opening and 7 is a cover attached to the other opening of the container. In Fig. 8, the fitting 8 is a reduction-nipple and 9 is a pipe or conduit connected therewith to convey the liquid from the container to another container provided with the fittings and openings of the container shown in Figs. 1

and 4, or to a container of different construction, or as desired.

From the foregoing description of the several figures of the drawings, it will be seen that the parts of the container described may, according to this invention, be fitted together without the employment of seams or solder, thereby avoiding the danger resulting from the employment thereof. It will also be seen that the conduits B are strongly supported at each end, being thereby protected against jars and the like and against pressure and blows of the liquid within the container during transportation or at other times. The conduits B may be finely perforated at the top and bottom of the sides, as shown at d d in Fig. 4, or they may be entirely closed along the sides, as shown in Figs. 1, 7 and 8, wherein openings D and gauze E provide communicating perforations, or they may be made of gauze, or finely perforated, as desired, but if perforations of conduits B themselves are used, the perforations should, preferably, be at the top and bottom of the sides, as shown in Fig. 4. The tube 1 leading through the perforations T and R, to the air-inlet P, as shown in Figs. 1 and 4, should, preferably, extend up through the conduit B so that its upper end is higher than the level of the liquid when the container is full.

As shown in Figs. 1 and 4, communication to the body of the container from the air-inlet P is had only through the tube 1 which passes through the conduit B, and communication from the inlet P and outlet Q to the body of the container is had only through the openings D which are covered by gauze E, making fine perforations, as shown in Fig. 1, or through the fine perforations d as shown in Fig. 4.

When liquid is to be poured into the container the upper opening of the container is uncovered, either by raising the valve 4 or by raising or removing any other fitting covering the upper opening of the container and the perforations R and S leading to the liquid-outlet Q and air-inlet P should, preferably, be closed, if the fitting L is attached to the other opening of the container. A funnel may then be placed in the conduit B and the liquid poured in. The liquid descends through the conduit B and, after filling the cavity l of the fitting L, enters the body of the container either through the lower openings D shown in Figs. 1, 7 and 8, or through the fine perforations d at the lower end of the conduit B, as shown in Fig. 4. While the liquid enters, air passes out through the upper openings D and gauze E, as shown in Figs. 1, 7 and 8, or through the fine perforations d at the upper end of the conduit B, as shown in Fig. 4. After the container has been filled,

the desired fitting should be replaced so as to protect and cover the upper opening of the container.

The channel of conduit B is, as shown, preferably open at each end and preferably continuous, that is unobstructed, from end to end. Where such conduit is provided with fine perforations near its ends and is otherwise closed, gases generated within the body of the container escape through the fine perforations at the upper end where, in the presence of flame within the conduit, they ignite. In case flame is present within the lower part of conduit B, as when, for example, some burning foreign substance falls within the conduit and the foreign substance coming in contact with the inflammable liquid therein continues to burn at the lower part of the conduit, heating the sides thereof, gases generated within the body of the container will, as stated, escape through the fine perforations at the upper end of the conduit, and, being ignited by the flame below, will, as shown by tests, cause the flame in the lower part of the conduit to be extinguished, whereupon the sides of the lower part of the conduit will cool down and, the gases ceasing to be generated within the body of the container and those generated having been consumed at the perforations near the upper part of the conduit, the flame at the perforations near the upper part of the conduit will go out and danger of explosion will be avoided.

When it is desired to draw liquid from a container provided at the lower opening thereof with the fitting L, shown in Figs. 1 and 4, the key X may be inserted into the key-hole and turned until the perforations S and R open respectively into the perforations U and T, whereupon liquid will flow out of the container through the liquid-outlet Q and air will simultaneously enter the container from the air-inlet P. The utility of drawing liquid of a volatile or inflammable character from a container in the manner described is clear, since the liquid is drawn from a container fully protected as described. Heretofore, in drawing volatile liquids from a container, some opening of the container has ordinarily been uncovered for the admission of air and through the uncovered opening gas from the container has accumulated in some inclosed place or closet in which the container has been kept, thus creating a dangerous condition apt to result in explosion. In drawing liquid, as described, from a container made in accordance with this invention, there is no leakage or accumulation of gas and no danger resulting therefrom. The liquid-outlet Q may be connected, as by screw-threads, with any suitable pipe or conduit to convey the liquid withdrawn to any point desired.

As shown in Figs. 1, 4, 9 and 10, the fitting L may be provided with an opening g, stopped or closed by a cap-screw g' or other suitable means, and the cap g' may be removed, when desired, either to drain off liquid, water or other foreign matter from the container or to allow any desired connection to be made, through or by means of the opening g.

10 As shown in Figs. 1 and 4, for example, a duct extends through the body of the container and the openings thereof. This duct may be constructed in different ways without departing from the principle of 15 this invention. As shown in Fig. 1, the duct may consist of the conduit B together with the collars C C adjusted to the ends thereof and of the fitting L with its cavity l; or, as shown in Fig. 4, the duct may consist 20 of the conduit B and of the fitting L with its cavity l. However constructed, the duct extends from one opening of the container to the other and is provided near its ends with perforations communicating with the 25 body of the container. As shown in Fig. 1, perforations D may be made in those parts of the duct formed by the collars C C; or, as shown in Fig. 4, perforations d may be made near the ends of the conduit B. As 30 appears from the foregoing description, communication to the body of the container from the duct can be had only through fine perforations impervious to flame, as the openings D covered by gauze, shown in 35 Fig. 1, or the fine perforations d, shown in Fig. 4.

Conduit B, extending from one opening 40 of the container to the other, provides a continuous or unobstructed channel from one opening of the container to the other. Protection is afforded to the body of the 45 container because, as stated, communication can be had from conduit B to the body of the container only through the fine perforations impervious to flame above described. Conduit B affords a channel 50 through which liquid may be poured into the container and in which the tube 1 for the admission of air can stand. The fine perforations impervious to flame, communicating from the upper end of conduit B to the body of the container, permit air and 55 gas to escape when liquid is poured into the container and permit gas to escape and burn in the manner described and thus avoid danger of explosion due to the presence of flame within conduit B. The fine perforations impervious to flame, communicating from the lower end of conduit B 60 to the body of the container, permit liquid poured into conduit B to enter and fill the body of the container and also protect the body of the container against flame present within conduit B. By a combination of parts in a manner such as that de-

scribed, the mode of operation and the several advantages pointed out may be obtained in accordance with this invention.

What I claim is:—

1. A container for liquids, provided with two openings and a duct having a continuous channel open at each end and adjusted to the container at each opening of the container, extending from one opening to the other and having perforations 70 communicating with the body of the container, the channel of the duct being at all times free from obstructions preventing the exit therethrough of gas passing through the perforations from the body of the container, substantially as described.

2. A container for liquids, provided with two openings and a duct having a continuous channel open at each end and adjusted to the container at each opening of the container, extending from one opening to the other and having perforations near its ends 85 communicating with the body of the container but otherwise closed, the channel of the duct being at all times free from obstructions preventing the exit therethrough of gas passing through the perforations from the body of the container, substantially as described.

3. A container for liquids, provided with two openings and a duct having a continuous channel open at each end and adjusted to the container at each opening of the container, extending from one opening to the other and having fine perforations near 95 its ends impervious to flame and communicating with the body of the container but otherwise closed, the channel of the duct being at all times free from obstructions preventing the exit therethrough of gas 100 passing through the perforations from the body of the container, substantially as described.

4. In a container for liquids provided with two openings, the combination of a duct, having a continuous channel open at each end and adjusted to the container at each opening of the container, extending from one opening to the other and having perforations communicating with the body 110 of the container, and a valve adjusted to the exterior of the container at one of the openings and over one end of the duct and free to rise on the outside of the container and uncover the duct, the channel of the 115 duct being at all times free from obstructions preventing the exit therethrough of gas passing through the perforations from the body of the container, substantially as described.

5. In a container for liquids provided with two openings, the combination of a duct, having a continuous channel open at each end and adjusted to the container at each opening of the container, extend- 120

- ing from one opening to the other and having perforations communicating with the body of the container, a valve adjusted to the exterior of the container at one of the 5 openings and over one end of the duct and free to rise on the outside of the container and uncover the duct, said duct comprising a suitable cap provided with a passage adjusted to the container at the other opening, 10 substantially as described.
6. In a container for liquids provided with two openings, the combination of a conduit extending from one opening to the other and a collar adjusted to the container at an opening thereof and at an end of the conduit, the adjustment of the collar at the end of the conduit being made so that the collar is free 15 from contact with the longitudinal extremity of the conduit, whereby the conduit will be free to expand and contract longitudinally, substantially as described.
7. In a container for liquids provided with an opening, the combination of a conduit adjusted to the container at the opening, a 20 collar adjusted to the outside of the container at the opening thereof and to the conduit, and a split ring adjusted about the opening to the inside of the container and to the collar, substantially as described.
8. In a container for liquids provided with two openings, the combination of a conduit extending from one opening to the other, a 25 collar adjusted to the container at an opening thereof and to an end of the conduit and a split ring adjusted about the opening to the container and to the collar, substantially as described.
9. In a container for liquids provided with two openings, the combination of a conduit 30 adjusted to the container at the openings and extending from one opening to the other, and a fitting covering one opening and adjusted to the container at the opening, the fitting being pierced by an air-inlet 35 channel and a liquid-outlet channel, each communicating with the body of the container, substantially as described.
10. In a container for liquids provided with two openings, the combination of a duct 40 adjusted to the container at the openings, extending from one opening to the other and having perforations communicating with the body of the container, said duct comprising a fitting adjusted to the container at one opening, the fitting being pierced by an air-inlet channel and a liquid-outlet channel, each communicating with the channel of the duct, substantially as described.
11. In a container for liquids, the combination of a cap, provided with a core having 45 a bore communicating at each end with the exterior of the container and two perforations through the core to the bore, each 50 perforation communicating at one end with the interior of the container and at the other end with the bore of the core, and a stopper located within the bore and pierced by two separated channels each communicating with a perforation of the core and with the exterior of the container, substantially as described.
12. In a container for liquids, the combination of a cap provided with a core having a bore communicating at each end with the exterior of the container and two perforations through the core to the bore, each 55 perforation communicating at one end with the interior of the container and at the other end with the bore of the core, and a rotatable stopper located within the bore and pierced by two separated channels each communicating with a perforation of the core and with the exterior of the container, substantially as described.
13. In a container for liquids, the combination of a cap provided with a core having a bore communicating at each end with the exterior of the container tapered at one end and two perforations through the core to the bore, each perforation communicating at one 60 end with the interior of the container and at the other end with the bore of the core, and a rotatable cylinder correspondingly tapered at one end located within the bore and pierced by two separated channels each communicating with a perforation of the core and with the exterior of the container, substantially as described.
14. In a container for liquids, the combination of a cap provided with a core having a bore communicating at each end with the exterior of the container tapered at one end and two perforations through the core to the bore, a rotatable cylinder correspondingly tapered at one end located within the bore and pierced by two separate channels communicating respectively with the perforations of the core and wider respectively than the perforations of the core at the points of juncture, and a spring pressing against the other end of the cylinder, substantially as described.
15. In a container for liquids, the combination of a cap provided with a core having a bore communicating at each end with the exterior of the container and two perforations through the core to the bore, each perforation communicating at one end with the interior of the container and at the other end with the bore of the core, a rotatable stopper located within the bore and pierced by two separated channels each communicating with a perforation of the core and with the exterior of the container, and a key adjusted to one end of the rotatable stopper, substantially as described.
16. In a container for liquids, the combination of a cap provided with a core having a bore, communicating at each end with

- the exterior of the container, and two perforations through the core to the bore and a pipe adjusted to the core about one perforation and extending therefrom into the body 5 of the container, each perforation communicating at one end with the interior of the container and at the other end with the bore of the core, substantially as described.
17. In a container for liquids, the combination of a cap provided with a core having a bore communicating at each end with the exterior of the container and two perforations through the core to the bore, a stopper located within the bore and pierced by two 15 separated channels each communicating with a perforation of the core and with the interior of the container, and a pipe adjusted to the core about one perforation and extending therefrom into the body of the container, each perforation communicating at one end with the interior of the container and at the other end with the bore of the core, substantially as described.
18. In a container for liquids, a hollow 25 cap provided with a core traversing the cavity of the hollow cap and having a bore, communicating at each end with the exterior of the container, and two perforations through the core to the bore, and with a 30 rotatable stopper located within the bore and pierced by two separate channels communicating respectively with the perforations of the core, substantially as described.
19. In a container for liquids provided 35 with an opening, a hollow cap adjusted to the container at the opening and covering the same, the hollow cap being provided in its shell with an opening communicating from its cavity with the interior of the body 40 of the container and with an opening communicating from its cavity with the exterior of the container and being provided also with a core traversing its cavity and having a bore communicating at each end with the exterior of the container and two 45 perforations through the core to the bore communicating with the interior of the container, and a rotatable plug within the bore, substantially as described.
20. In a container for liquids provided 50 with two openings, the combination of a duct adjusted to the container at the openings, extending from one opening to the other, and having perforations communicating with the body of the container, and a 55 suitable fitting adjusted to and covering one end of the duct said duct comprising a fitting adjusted to the container and provided with a core having a bore and two perforations through the core to the bore and with a 60 rotatable stopper located within the bore and pierced by two separate channels communicating respectively with the perforations of the core, substantially as described.
21. In a container for liquids provided 65 with two openings, the combination of a duct adjusted to the container at the openings, extending from one opening to the other, and having perforations communicating with the body of the container, said 70 duct comprising a fitting adjusted to the container and provided with a core having a bore and two perforations through the core to the bore, and a pipe extending through the duct and adjusted at one end 75 to the core about one of the perforations of the core, substantially as described.

WILLIAM ASBURY.
